BARBECUE BROILER

Robert H. Gibbs, Vista, Calif.

Application December 18, 1957, Serial No. 48,950

Term of patent 14 years

(Cl. D81—10)

I claim:

The ornamental design for a barbecue broiler, substantially as shown.
